UNITED STATES PATENT OFFICE.

JOHN MANCHESTER, OF NORTH LOUP, NEBRASKA.

POULTRY PERCH.

Application filed October 28, 1922. Serial No. 597,579.

To all whom it may concern:

Be it known that I, JOHN MANCHESTER, a citizen of the United States, and a resident of North Loup, in the county of Valley and State of Nebraska, have invented certain new and useful Improvements in Poultry Perches, of which the following is a specification.

This invention relates to poultry perches and has for its object the provision of a device adapted to contain a medicated solution which will saturate the perch to prevent mites and other vermin from infesting and propagating on the perch.

Other objects and objects relating to details in construction will hereinafter appear.

The invention is illustrated by way of example in the accompanying drawings, in which,

Figure 1 is a view in perspective of a section of the perch with the longitudinally disposed channel closed by a cover.

Figure 2 is a view in perspective of a section of the same with the cover removed.

Figure 3 is a longitudinal section of the perch.

Figure 4 is a transverse section of the perch.

Referring to the drawings, 1 indicates a bar provided with a groove 2 cut into the upper face of the bar and extending from end to end of the bar. The bar is also provided with a longitudinal channel 3 cut into the body of the bar and below the groove 2, with the channel extending longitudinally of the bar and terminating adjacent the opposite ends thereof. The ends of the channel are curved upwardly as at 4 toward the upper face of the bar and leading into the longitudinal groove and likewise curved outwardly toward the ends of said bar.

The longitudinal groove 2 extends from end to end of the bar so that the base portions 5 of the groove adjacent the ends 6 form seats for the ends of the cover 7.

The groove 2 and channel 3 cooperate to form shoulders 8 running longitudinally upon opposite sides of the channel 3 and forming a seat for the longitudinal edges 5 of the cover 7. The cover 7 is adapted to snugly fit between the longitudinal sides of the channel when seated on the shoulders 5 and 8 of the bar 1, the cover being friction-

ally retained on its seat by the sides of the groove 2. Adjacent one end of the cover 7 is formed a perforation 9 which is adapted to receive a cork 10. The perforation 9 is adapted to provide an opening for the admission of some form of medicated solution which is adapted to saturate the wood, and prevent mites or other vermin from infesting the perch.

It will be noted that the channel 3 is sealed sufficiently by the cover and the co-operating sides of the groove 2 to prevent any dirt from working its way into the channel 3. By reason of this closure of the channel 3 said channel is always maintained clean and therefore it will be unnecessary at any time to remove the perches to clean the interior of the same.

Since the cover 7 is frictionally retained between the side walls of the groove 2 it will be only necessary to raise the cover when desiring to remove the same. If the cover were slidably mounted in undercut grooves over the channel 3 it would be necessary to remove the perch entirely or have openings provided in the side of the chicken coop to slide the cover through the same.

What I claim is:

A poultry perch comprising a bar provided with a groove cut into the upper face of the bar and extending from end to end of said bar, said bar having a channel cut into the body of the bar and below the groove, said channel extending longitudinally of the bar and terminating adjacent the opposite ends thereof, with the ends of the channel curved upwardly toward the groove and outwardly toward the end of the bar, the groove and channel cooperating to form shoulders on opposite sides of the channel and below the upper face of the bar, an elongated cover adapted to be snugly fitted within the groove and seat upon the shoulders and the opposite grooved ends of the bar for closing the channel, said cover being frictionally engaged by the sides of the groove and provided with a perforation at one end forming an opening for filling the channel with a disinfectant and a cork removably mounted in the perforation for sealing the contents of the channel from the atmosphere.

JOHN MANCHESTER.
